UNITED STATES PATENT OFFICE

2,470,502

SEWING MACHINE

Harold J. Le Vesconte, Glendale, Calif., and Oscar Quist, Chicago, Ill., assignors to Union Special Machine Company, Chicago, Ill., a corporation of Illinois

Application October 20, 1945, Serial No. 623,536

7 Claims. (Cl. 112—214)

1

This invention relates to improved work feeding mechanisms for sewing machines and more particularly to improved continuous wheel feed mechanisms. It is of special advantage when applied to a sewing machine of the needle feed type and one which is equipped with a rotary hook for the formation of lock stitches.

A primary object of the invention has been to provide a simple, sturdy, and efficient mechanism of the character above indicated, which is inexpensive to construct.

It has been a further object of the invention to provide a continuous wheel feed mechanism which is quiet and reliable in operation and which may readily have its speed varied at will in relation to the speed of the main drive shaft of the machine. This provides for appropriate variation of the feed in accordance with the length of the stitch desired.

A special feature of the invention is the provision of a machine of the above indicated type with a completely sealed and effectively lubricated gear reduction unit which forms a part of the connection between the main drive shaft of the machine and the continuously driven feed wheel.

Another important feature of the invention is the provision of a change gear mechanism capable of varying the speed of the feed wheel, and hence the length of the stitch, which is substantially noiseless in its operation. This is, in part, accomplished through the provision of an arrangement by which only two gears are in mesh for any selected speed of operation of the feed wheel. In addition to reducing noise, this arrangement also reduces wear on the gears and thus lengthens the life of the mechanism.

Still another feature of the invention is the provision of a readily adjustable positive positioning means for varying the height of the feed wheel in relation to the work supporting surface.

Other features, objects, and advantages of the invention will appear from the detailed description of an illustrative form of the same, which will now be given in conjunction with the accompanying drawings, in which:

Figure 1 is a longitudinal vertical section through the illustrative machine;

Figure 2 is an enlarged detail view, partly in elevation and partly in vertical section, illustrating the feed wheel and associated presser means forming part of the invention;

Figure 3 is an end elevational view of the machine as seen from the left end of Figure 1;

Figure 4 is a vertical sectional view on an enlarged scale taken along the line 4—4 of Figure 1;

2

Figure 5 is a bottom plan view of the machine with a bottom cover plate, provided adjacent the righthand end of the machine, removed and with portions at the lefthand end broken away to more clearly illustrate the construction;

Figure 6 is an enlarged detail view in vertical section, taken along the line 6—6 of Figure 1;

Figure 7 is an enlarged view, partly in bottom plan and partly in section, of the lefthand end 10 portion of the machine as shown in Figure 5; and

Figure 8 is an end elevational view of the needle head portion of the machine with the cover plate and certain thread takeup means removed.

Referring now to the drawings, the illustrative 15 machine comprises a frame having a base or work supporting portion 10, a vertical standard 11, and an overhanging arm 12 terminating in a needle head 13. Power is supplied to the machine through a combined handwheel and pulley 14 adapted to be connected by a belt with an electrical transmitter, or any other suitable source of power. This pulley is secured to a main drive shaft 15 which extends through the end wall of the vertical standard near its top and longitudinally through the overhanging arm 12 into the 20 needle head. It is mounted in suitable bearings in a manner well known in the art. At its end within the needle head the shaft 15 carries an eccentric member 16, preferably of counter balanced construction, having an eccentric pin or crank connected by means of a link 17 with a block 18 secured to a needle bar 19 which carries at its lower end one or more needles 20. The needle bar is mounted for vertical reciprocation 25 within a yoke-like sleeve member 21 which is pivotally mounted for rocking about a pin 22 at its upper end. The yoke member 21 has an offset portion 23, in the region where the block 18 is connected to the needle bar, and below the offset portion member 21 carries a further bearing 24 for the needle bar. It will be apparent that upon each revolution of the shaft 15 the needle bar will be reciprocated longitudinally within the yoke member 21 by means of the eccentric 16. This 30 will serve to carry the needle 20 downwardly through the work into cooperation with the complementary stitch forming means in the base and back to the position indicated in Figure 1.

In the machine illustrated, provision is made 35 for simultaneously imparting a rocking movement to the yoke member 21 so as to cause the needle to shift, while it is in cooperation with the work, in synchronism with the work feeding means. The mechanism for imparting 40 this needle-feed movement to the needle bar may

be similar to that disclosed in the patent to Quist No. 2,329,484, granted September 14, 1943, to which reference may be had for a full disclosure of this construction. For the purposes of the present invention it will be but briefly described. Projecting inwardly from the offset portion 23 of the yoke member 21 is a stud 25 which is connected by a link 26 (Figures 1 and 3) with an arm 27 secured to a sleeve or hollow shaft 28 surrounding the shaft 15 and providing suitable bearings for the latter. Sleeve 28 is suitably journalled in bearings within the overhanging arm. At its right-hand end the sleeve 28 carries an arm 29 (Figures 1 and 4) which is pivotally connected at its lower end with a bearing block 30. The latter provides a bearing for a slideable rod 31 which at its upper end is also slideable within a yoke member 32 having an eccentric strap portion cooperating with an eccentric 33 secured to the shaft 15. Rod 31 carries a block 34 which is secured to the rod by means of set screws 35 and which is pivotally supported at 36 by a member 37 secured to a vertically shiftable rod 38. The axial position of the rod 38 within its bearings may be varied as desired by turning a knob 39 carrying a screw threaded stem 40 cooperating with a threaded portion of the rod 38. In this manner the location of the pivot 36 about which rod 31 is rocked may be varied and thus the extent of rocking of the system including rod 31 and arm 29 may be varied. This rocking movement is imparted by the eccentric 33 which tends to carry the yoke 32 both up and down and toward the right and left in Figure 4. Its right and left movements are imparted to the rod 31 to rock the latter and this rod, in turn, through the connection 30 rocks the arm 29, sleeve 28, and yoke 21 by virtue of the connections described. In this manner needle feed movements of desired magnitude are imparted to the needle simultaneously with the reciprocation of the needle bar.

Within the vertical standard 11, suitable gearing is provided for connecting the main shaft 15 with a shaft 41 within the base portion of the machine. This gearing comprises a pinion 42 secured to the shaft 15, an idler gear 43 mounted within the standard, and a pinion 44 secured to the shaft 41. Shaft 41 is mounted in suitable bearings provided by downwardly extending walls 45 and 46 of the frame, which together with front and rear walls 47 and 48 (Figure 4) form an enclosure constituting a continuation of the space within the hollow standard. A removable cover plate 49 secured in any suitable way to the lower ends of the walls 45, 46, 47, and 48, serves to complete the enclosure. A lug 50 extending downwardly from the work supporting portion 10 of the frame provides a further bearing for the shaft 41. At its outer end, this shaft carries a helical gear 51 meshing with a corresponding gear 52 on a vertical axis hook unit 53 of suitable construction. This may, for example, be of the type disclosed in the above mentioned Quist patent. It will be understood that the vertical hook cooperates with the needle 20 in stitch formation upon operation of the machine. Due to the relative diameters of the gears 51 and 52 the hook will be driven at a 2 to 1 speed in relation to the speed of the main shaft.

Secured to the shaft 41 within the enclosed chamber formed by the standard 11 and the downward extension thereof, as above described, is a worm 54 which meshes with a worm wheel 55 secured to a shaft 56 (Figures 1 and 4) journalled

in suitable bearings 57 and 58 in the front and rear walls of the frame. Also secured to the shaft 56 is a worm 59 which meshes with a worm wheel 60 secured to a shaft 61. This shaft extends from within the enclosed chamber, where it carries the worm wheel 60, outwardly through the wall 45 to the outer end of the work support 10. It is journalled in suitable bearings 62 and 63 adjacent its outer end. Beyond the bearing lug 63 the shaft carried a plurality of gears 64, 65, and 66 having different numbers of teeth. One or another of these gears is adapted to mesh with its corresponding gear 67, 68, and 69 carried by and secured for rotation with, a sleeve 70 slidably mounted and keyed for rotation with a shaft 71. Shaft 71 terminates adjacent downwardly extending lug 72 at the outer end of the work supporting member. The shaft is journalled in a bearing sleeve 73 carried by an arm 74 rockably mounted by means of a sleeve or hub 75 carried by the shaft 61. Sleeve or hub 75 is held against axial movement along shaft 61 by means of collars 76 at its opposite ends. Arm 74 is forked to straddle a screw 77 having threaded engagement with an opening in the under side of the work support. The axial position of screw 77 may be varied, as desired, by turning a knob 78. A spring 79 coacting beneath the underside of the work support and the top of the forked portion of the arm 74 serves to urge the latter downwardly until V-shaped projections 80 on the forked portion cooperate with corresponding notches in the upper face of the knob 78. The coaction between the V-shaped members 80 and the notches serves to hold the knob 78 in any position to which it may be adjusted. Adjacent the righthand end of the bearing sleeve 73 the shaft 71 carries a feed wheel 81, the periphery of which is preferably knurled or serrated to assist in the desired feeding action. This wheel may be secured to the shaft in any suitable way, as by means of a nut 82, as shown in Figure 5. Feed wheel 81 is adapted to project upwardly through a suitable opening 83 in a throat plate 84 carried by the work support. The extent to which the wheel 81 projects through the opening 83 and above the upper surface of the throat plate may be varied as desired by turning the knob 78. This knob, as will be seen, is readily accessible below the work support so that the desired adjustment may be effected with facility.

In the illustrative machine the reduction gearing, comprising the worm 54, worm wheel 55, worm 59, and worm wheel 60, is such as to effect a reduction of 200 to 1. For this purpose a reduction of 20 to 1 is effected between worm 54 and wheel 55 and a further reduction of 10 to 1 is effected between worm 59 and wheel 60. Thus for 200 revolutions of the shaft 41, or of the main shaft 15, the shaft 61 will be given but a single revolution. While this has been found to be a desirable reduction for the purposes of the illustrative machine, it will be understood that it may be varied to suit the particular requirements of any machine.

A variation in the speed of rotation of the feed wheel 81 in relation to that of shaft 61 may be accomplished at will by simply sliding the sleeve 70 axially of the shaft 71. When the parts are in the position indicated in Figure 5, in which gear 66 meshes with gear 69, the shaft 71 will be given its slowest speed; hence the rate of feed will be at the minimum. If sleeve 70 is shifted outwardly, i. e., toward the left in Figures 5 and 7, to engage gear 68 with gear 65, the shaft 71, and

hence the feed wheel, will be given their fastest movement. If the sleeve is shifted to its outermost position, as shown in Figure 7, to mesh gears 64 and 67, the shaft 71 and the feed wheel will be given their intermediate speeds of movement. The end 70a (Fig. 1) of the sleeve 70 may suitably be knurled to facilitate grasping it by the fingers and shifting it as desired. For the purpose of retaining the sleeve 70 in a selected axial position in relation to the shaft 71, a key 85 retained within a key slot in the shaft 71 has a centrally disposed teat 86 on its outer surface adapted to cooperate with any one of a series of three openings 87 in the sleeve 70. Key 85 is urged outwardly by a leaf spring 88 to retain the teat 86 yieldingly in engagement with the selected opening 87. Key 85 may also form the driving connection between the shaft 71 and sleeve 70, it being adapted to slide along a keyway within sleeve 70 during the adjustment of the latter.

It will be noted that the change gear mechanism provided by the gears 64 to 69 inclusive, provides for the meshing of only two gears at a time. All of the gears 64, 65, and 66 rotate together as do all of the gears 61, 68, and 69. However, only one gear of each set will be active at any particular time. This serves to eliminate considerable wear on the gears and noise incident to meshing of a greater number of gears.

Cooperating with the feed wheel 81 there is preferably provided a presser wheel 89, which is carried by an arm 90 mounted in any suitable way upon the lower end of a vertically movable presser bar 91. The latter, as best shown in Figure 8, is vertically slidable in suitable bearings within the needle head. It is urged downwardly by a spring 92 acting at its lower end upon a lug 93 secured to the presser bar and acting at its upper end against the bottom of a screw threaded sleeve 94. The latter may be adjusted to any desired height within the needle head frame by rotation of the sleeve through the aid of a knob 95 at its upper end. Any suitable means may be provided for lifting the presser bar, thus raising the wheel 89 whenever desired for the introduction or removal of work, or the like. This lifting means may, for example, comprise a sleeve 96 slidably carried by the presser bar and attached to the lower end of a link 97 depending from an arm 98 secured to a rock shaft 99. The latter may suitably extend longitudinally of the overhanging arm to a point adjacent the standard and there carry an arm 100 (Figure 3) connected by a link 101 (see also Figures 1 and 5) with an arm 102 of a rock member pivotally carried by the base of the machine. Another arm 103 of this member may be connected in any suitable manner with a foot treadle or knee control member or the like, not shown. Lifting of the presser bar may also be manually accomplished, if desired, by means of a lever 104 (Figure 3) arranged to cam the lug 93 upwardly in a conventional manner.

It will be understood that the machine embodying the present invention will be equipped with the usual adjuncts for supplying and controlling the thread for the needle or needles. The means for this purpose which has been partially illustrated, including a rotary take-up mechanism, need not be described since it does not form a part of the present invention.

In the operation of the machine the needle will be reciprocated once upon each rotation of the shaft 15 and it will be oscillated in the manner explained to impart a needle feed action upon

each such rotation. At the same time, through the gearing 42, 43, and 44 and the reduction gearing described in the foregoing, the complementary means within the base will be driven. The rotary hook, for example, will be driven directly by the shaft 41 but at a 2 to 1 ratio. The feed wheel 52 will be driven at a greatly reduced speed by virtue of the reduction gearing and at a selected specific speed determined by the axial adjustment of the sleeve 70 in relation to the shaft 71. The adjustment of the needle feed control member 39 and the adjustment of the sleeve 70 should preferably coincide so that the continuous feed imparted by the wheel 81 will correspond with the needle feed action. The wheel 81, however, may be driven at a slightly greater peripheral speed than the feed movement imparted by the needles to allow for relative slippage between the feed wheel and the work.

20 In the operation of the gearing within the standard and the downward extension of the base, oil retained within the sump formed by this downward extension, will be whipped into a spray both by the gear 44 and the worm wheel 60 to insure thorough lubrication of all of the relatively sliding surfaces within the enclosed portion of the frame. In this way the major lubrication problems of the machine, including lubrication of the speed reducing gearing, are taken care of.

25 While an illustrative machine has been described in considerable detail, it will be understood that numerous changes may be made in the construction and arrangement of the various parts without departing from the general principles and scope of the invention as defined by the appended claims.

We claim:

1. In a sewing machine, a frame having a base, a vertical standard and an overhanging arm, said base and standard combining to provide a lubricant retaining housing, a power receiving shaft extending into said housing, a continuously driven work feeding wheel mounted in said base, an operating shaft for said wheel which extends into said housing, and reduction gearing within said housing for interconnecting said power receiving shaft and said operating shaft, said gearing being arranged to disperse lubricant within said housing to lubricate the relatively moving surfaces therein including all of the gearing connecting said power receiving shaft with said operating shaft.

2. In a sewing machine, a frame having a base, a vertical standard and an overhanging arm, said base and standard combining to provide a lubricant retaining housing, a power receiving shaft extending into said housing, a continuously driven work feeding wheel mounted in said base, a supporting shaft for said wheel, stitch forming means including a rotary hook within said base, operating shafts for said wheel and for said hook, said operating shafts extending into said housing, connections from said power receiving shaft to the operating shaft for said hook for driving the latter, and reduction gearing within said housing for interconnecting said operating shafts to drive the operating shaft for said wheel through the operating shaft for said hook, the lubricant in said housing being dispersed therein by said connections and gearing.

3. In a sewing machine, a frame having a base, a vertical standard and an overhanging arm, said base and standard combining to provide a lubricant retaining housing, a power receiving

shaft extending into said housing, a continuously driven work feeding wheel mounted in said base, a supporting shaft for said wheel, stitch forming means including a rotary hook within said base, operating shafts for said wheel and for said hook, said operating shafts extending into said housing, connections from said power receiving shaft to the operating shaft for said hook for driving the latter, and reduction gearing within said housing for interconnecting said operating shafts to drive said wheel operating shaft from said hook operating shaft, said reduction gearing being arranged to disperse lubricant within said housing to lubricate the relatively moving surfaces therein.

4. In a sewing machine, a frame having a base, a vertical standard and an overhanging arm, said base and standard combining to provide a lubricant retaining housing, a power receiving shaft extending into the upper portion of said housing, a continuously driven work feeding wheel mounted in said base, a supporting shaft for said wheel, stitch forming means including a rotary hook within said base, operating shafts for said wheel and for said hook, said operating shafts extending into said housing, change speed gearing directly connecting one of said operating shafts with said wheel supporting shaft, connections from said power receiving shaft to the operating shaft for said hook for driving the latter, and reduction gearing within said housing for interconnecting said operating shafts for driving the wheel operating shaft from said hook operating shaft, said connections serving to distribute the lubricant throughout said housing.

5. In a sewing machine, a frame having a base, a vertical standard and an overhanging arm, said base and standard combining to provide a lubricant retaining housing, a power receiving shaft extending into said housing, a continuously driven work feeding wheel mounted in said base, a supporting shaft for said wheel wholly outside of said housing, stitch forming means including a rotary hook within said base, operating shafts for said wheel and for said hook, said operating shafts extending into said housing, change speed gearing outside of said housing directly connecting one of said operating shafts with said wheel supporting shaft, said gearing comprising a plurality of gears fixed to said one of said operating shafts and a plurality of cooperating gears slidable on said supporting shaft for selective meshing with one of the gears on said operating shaft, connections within said housing from said power receiving shaft to the operating shaft for said hook for driving the latter,

and reduction gearing within said housing for interconnecting said operating shafts and driving the wheel operating shaft from the hook operating shaft.

5. In a sewing machine having a work supporting base, a continuously rotatable feed wheel in said base and a main power receiving shaft, means for driving said wheel at different speeds which comprises a feed wheel operating shaft, reduction gearing connecting said shafts, a feed wheel supporting and driving shaft, a set of gears of different diameter mounted for rotation with said operating shaft, a set of gears of different diameter mounted for rotation with said wheel supporting shaft, a sleeve carrying and rotatable with one of said sets of gears, said sleeve being keyed to but slidably axially of the shaft on which said set of gears is mounted to engage a selected one of said gears with a gear of the other set, and means coaxing between said sleeve and said last mentioned shaft for retaining said sleeve in selected position on its shaft.
7. In a sewing machine having a work supporting base and a continuously rotatable feed wheel in said base, a shaft for supporting said wheel, an operating shaft, gearing connecting said operating and supporting shafts for rotation in synchronism, said gearing comprising a set of gears of different diameters on each of said shafts, the gears of one set being shiftable axially in relation to the gears of the other set to selectively engage a gear of each set with a corresponding one of the other, a member carrying said supporting shaft, said member being rockably carried by said operating shaft, and means for turning said member about said operating shaft and retaining it in set position for adjustment of said feed wheel, said means being disposed forwardly of said supporting shaft and comprising a rotatable adjusting screw and means for locking said screw in adjusted position.
